(57) **CLAIM**

The ornamental design for a biopsy device, as shown and described.

DESCRIPTION

FIG. 1 is a top perspective view of a biopsy device, showing our new design;

FIG. 2 is a bottom perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The needle assembly, collection assembly, device stands, speaker apertures, soft buttons, and icon regions shown in broken lines are unclaimed subject matter and form no part of the claimed design.
